UNITED STATES PATENT OFFICE

PHILIP C. CLARKE, OF WEST COLLINGSWOOD, NEW JERSEY, ASSIGNOR TO GENERAL ELECTRIC COMPANY, A CORPORATION OF NEW YORK

SWITCH OPERATING MECHANISM

Application filed February 28, 1930. Serial No. 432,233.

My invention relates to switch operating mechanism and more particularly to operating mechanism of the quick-acting type for circuit breakers having large power interrupting capacities.

In modern interconnected power systems involving vast quantities of power, it is possible that a disturbance of brief duration at some part of the network may cause such instability that some of the generating units drop out of synchronism. It is therefore highly desirable, if not essential, that the fault, which may be a short circuit, for example, be isolated from the system as quickly as possible in order to maintain the stability thereof within reasonable limits. Accordingly, the duty of isolating the fault before any of the generating units pull out of step falls upon the circuit breakers in that particular part of the system.

In circuit breakers, as of the oil type for example, the total duration of the opening operation may be divided into several periods, namely; the time required to disengage the trip mechanism of the breaker and start the movable contact structure in motion; the time from the start of motion to the separation of the contacts, and the time from the separation of the contacts to the interruption of the circuit. The duration of operation may therefore be considerably reduced by increasing the speed of the tripping mechanism and by causing quick positive opening of the contact structure immediately in response to the tripping operation.

It is an object of my invention to provide high speed tripping and operating mechanism for large capacity circuit breakers which shall be simple in construction, and reliable and positive in action.

It is a further object of my invention to provide a high speed opening mechanism for circuit breakers wherein an energy storing operation is effected prior to the circuit closing operation for causing a subsequent opening of the breaker.

It is a further object of my invention to provide, in a high speed opening mechanism for circuit breakers, mechanism for storing energy in a compression spring for effecting

opening of the circuit breaker at high speed, and mechanism for causing closing movement of the circuit breaker subsequent to compression of said spring, said mechanisms being interconnected by coupling means whereby trip-free action of the circuit breaker at any time during its closing movement may be obtained.

My invention will be more fully set forth in the following description referring to the accompanying drawing, and the features of novelty which characterize my invention will be pointed out with particularity in the claims annexed to and forming a part of this specification.

Referring to the drawings, Fig. 1 is a diagrammatic illustration of high speed operating mechanism embodying my invention associated with a circuit breaker; Fig. 2 is a diagrammatic illustration of part of the mechanism illustrated in Fig. 1 in another position; Fig. 3 is a diagrammatic illustration showing the mechanism in still another position; Figs. 4 and 5 are views partly in section of an alternate form of mechanism adapted to be used in Figs. 1-3; Fig. 6 is a diagrammatic illustration of another form of my invention; Figs. 7, 8 and 9 are detailed views of apparatus illustrated in Fig. 6 shown in different operating positions and Figs. 10, 11 and 12 are views of another alternate form of mechanism shown in different operating positions.

In Fig. 1 there is illustrated operating mechanism associated with a circuit breaker of the fluid-break type. In the present instance, but without limitation of my invention thereto, an oil circuit breaker provided with explosion chambers is employed comprising an operating rod 1 carrying the movable bridging contact structure 2 and the contact rods 3. The stationary contacts for coacting with the movable contact rods are disposed within the explosion chambers 4, which may be of well known construction, and are mounted at the lower portions of the insulating bushings 5. The operation of this type of circuit breaker is well known, it being necessary simply to mention that downward movement of the operating rod 1 causes

separation of the contacts within the explosion chamber, the pressure generated by the arcs within the chambers being effective to force oil out the lower end of the chambers 5 for extinguishing the arc. The closing operation of the breaker is effected by simply moving the operating rod upwardly from the position shown until the contact rods 3 properly engage the stationary contacts with- 10 in the corresponding explosion chambers.

For the purpose of transmitting motion to the operating rod 1, there is provided suitable straight-line linkage mechanism comprising a longitudinally movable rod 6 connected at 15 one end, as at 7, to one arm of a bell crank 8 having a fixed pivot 9. The other end of the bell crank is connected as at 10 to a link 11 likewise connected as at 12 to a second bell crank 13 having a fixed pivot 14. The 20 opposite end of the bell crank 13 is connected through a link 15 to one end of the lever 16 centrally pivoted as at 17 and having its other end connected at 18 to the mid portion of a link 19, one end of which is connected as at 25 20 to the operating rod 1, the other end being connected to a link 21 pivoted at 22. It will be noted therefore that reciprocal movement of the rod 6 causes reciprocal movement of the pivot point 20 and therefore the switch 30 operating rod 1 by reason of the straight-line linkage mechanism 16, 19 and 21. Accordingly, downward movement of the rod 6 is effective to cause closing or upward movement of the operating rod 1, and vice versa. 35 The motive power for actuating the rod 6 so as to cause either opening or closing of the circuit breaker comprises in the present instance two electro-motive devices 23 and 24, as electric motors for example, and an 40 energy storing device, as a strong compression spring 25, for example. It shall be understood, of course, that in lieu of the motors 23 and 24, other motive means, as solenoids, hydraulic operators or other suitable sources 45 of power may be used.

The function of the motor 23 is to store energy solely for the opening operation of the circuit breaker, and to this end it is operatively connected to the compression spring 25 50 through the well known centrifugal flyball operating linkage 26, a link 27 centrally pivoted as at 28, and compound toggle structure presently to be described. The link 27 is connected at its operating end to a link 27' which 55 is in turn connected to the central pivot of a toggle 29-29'. For the purpose of controlling the toggle 29-29', a second toggle 29'-30, forming therewith a compound toggle, is provided. The link 30 of this second 60 toggle has a fixed pivot at 30', the other end of the link comprising the central pivot of the toggle which is controlled by tripping means hereinafter described. A bell crank 31 having a fixed pivot 32 is connected to the toggle 65 29-29' and also, as at 33, to a bearing plate

34 coacting with the movable end of the compression spring 25 which is seated at its opposite end on a stationary support 35. The bearing plate 34 is provided with a portion 36 adapted to abut under predetermined conditions a corresponding member 37 carried by one end of the rod 6.

The function of the motor 24 is to effect closing movement of the switch operating rod 1, and for this purpose the motor is operatively connected in the manner above described to the rod 6 through the fly-ball operating linkage 38, centrally pivoted link 39, the connecting link 39', toggle 40-40', and a bell crank 42 pivoted at 43, and having one 80 arm connected as at 44 to the toggle 40-40', and the other arm pivotally connected to a collar 45 or the like secured to the rod 6. As in the previous instance the toggle 40-40' forms part of a compound toggle arrangement comprising the second toggle 40'-41. The toggles interconnecting the motors with the compression spring and switch operating rod respectively, are each controlled by a common trip mechanism comprising a tripping toggle 46-46' whose central pivot is provided with a roller 47 adapted to be engaged and restrained in position by a tripping lug 48 pivoted at 49. The tripping lug 48 may be moved out of the path of the central pivot roller 47 by any suitable means, as for example, an extension 50 adapted to be engaged by the movable core 51 of an over-load or tripping magnet. The tripping toggle is provided with a fixed pivot 52 at one end 100 and is pivoted at its other end to a link 53 connected at its opposite ends, as at 54 and 55, to the respective compound toggle arrangements above referred to. It will therefore be noted that the link 53 is effective, when the tripping toggle 46-46' is locked by the lug 48, to permit straightening of the toggles 29-29' and 40-40' for causing clockwise rotation of the bell cranks 31 and 42 respectively, and to permit buckling or collapse of said toggles and 110 consequent counterclockwise movement of the bell cranks when collapse of the tripping toggle allows upward movement of the link 53. In other words, when the link 53 is restrained in the position illustrated in Fig. 1, the pivots 55 and 54 are stationary with the result that the toggles 29-29' and 40-40' may be straightened as simple toggles.

Referring now to Fig. 2, and assuming that the apparatus was previously in the position 120 illustrated in Fig. 1, the apparatus is illustrated in a preliminary circuit closing position wherein the motor 23 has been independently energized through suitable circuit connections to cause compression of the 125 spring 25. During this operation, the link 27 is rotated counterclockwise by the flyball operating linkage, thereby straightening the toggle 29-29' and rotating the bell crank 31 in a clockwise direction to compress the spring 130

25. The movement of the apparatus is limited by the stop member 31' which is engaged by the central pivot of the toggle when the spring has been compressed a desired extent.

5 During the aforesaid operation the bearing member 36 moves away from the rod 6 which remains stationary. As illustrated in Fig. 2, the spring compressing toggle 29-29' is straightened to a slightly overset or locking position so that it is capable of holding the spring 25 in its compressed position against the reaction thereof. The motor 24 is suitably energized subsequent to energization of the motor 23 so that the compression of the spring 25 and the movement of the rod 6 may be effected independently of each other.

The apparatus illustrated in Fig. 3 shows the operating mechanism in the fully closed position wherein the motor 24 has moved the rod 6 to its circuit closing position so that it again abuts the bearing member 36 of the compression spring. As in the previous spring compressing operation, the toggle 40-40' is straightened by the flyball operating linkage 38 to cause clockwise movement of the bell crank 42 and consequent closing of the breaker. The toggle 40-40' is likewise straightened to a slightly overset position and engages at its central pivot the stop member 42' so as to lock the circuit breaker closed. It shall be noted therefore that the circuit breaker is maintained and locked in its closed position as long as the toggles 29-29' and 40-40' assume the locking positions illustrated in Fig. 3.

In case the circuit breaker is to be opened in response to some abnormal circuit condition in the system, the magnetic member 51 engages the extension 50 of the tripping lug so as to move it in a clockwise direction out of the path of the central-pivot roller 47 of the locking toggle. It will be obvious, of course, that a suitably operated manual device may be employed if desired. With the toggle 46-46' now free to collapse, the reacting forces exerted along the toggles 29-29' and 40-40' cause sudden upward movement of the link 46, now that the pivots 55 and 54 are no longer held stationary, with the result that the aforesaid toggles have their lines of centers shifted so that they are now undertravelled and free to collapse. Since the toggles collapse practically simultaneously, the rod 6 is at once urged upwardly by the powerful compression spring 25 so that the operating rod 1 is moved at high speed to its open circuit position.

60 It shall be noted that the compression spring 25 is effective to cause opening of the circuit breaker practically simultaneously with the buckling of the locking toggle 46. Since the tripping magnet may cause buckling of the toggle within a very short time, it

is apparent that the operation of the breaker is particularly rapid.

For the purpose of returning the various toggle and flyball linkages to the positions illustrated in Fig. 1, suitable resetting means, as springs or weights (not shown) may be employed.

70 Trip-free action of the circuit breaker operating mechanism is generally desirable, since certain conditions existing in the system may make closing or reclosing of the breaker inadvisable. By trip-free action is meant the tripping of the breaker mechanism at any time during its closing movement regardless of the application of the closing force. In the arrangement shown in Figs. 1 to 3, trip-free action is of course possible, but due to the fact that the members 36 and 37 would very likely be spaced from each other at the moment of tripping, unless the motors are synchronized to effect the spring compressing and switch closing operations simultaneously, the rod 6 would be subjected to the impact of the released compression spring. It is therefore essential that suitable coupling means be provided for enabling the spring 25 when released at any time during the switch closing movement, to act upon the operating rod 6 without shock or impact where trip-free action is desired.

75 In lieu of the mechanical engagement between the compression spring 25 and the rod 6, there may be provided suitable unidirectional thrust-transmitting coupling means, as a hydraulic coupler, for example, of the character illustrated in Figs. 4 and 5. As in the previous arrangement, the bell crank 31 is connected through a bearing member 34' to the compression spring 25', and the bell crank 42 is pivotally connected to the rod 6. For the purpose of permitting compression of the spring by operation of the bell crank 31 independently of the bell crank 42, and for transmitting energy at any time during the closing movement of the switch from the compression spring to the rod 6, there is provided a hydraulic cylinder 60 fixed in any suitable manner to the lower end of the rod 6 and having at its opposite end an end wall 61 within which is guided a piston rod 62 connected to a piston member 63. The piston member 63 is provided with fluid passages 64 which are adapted to be closed by a valve member 65 seating on the upper side of the piston. The valve 65 is provided with a valve stem 66 extending through a bore within the piston rod 62 and terminating in an extension 66'. The valve 65 is therefore free to move with respect to both the piston 63 and the cylinder 60. The bell crank 31 is pivotally connected as at 67 to the piston rod 62 exteriorly of the cylinder so that the spring compressing operation tends to draw the piston 63 downwardly with respect to the cylinder 60. The cylinder 60 is provided with a suitable hydraulic medium,

80

95

100

105

110

115

120

125

130

as oil, for example, so that the piston 63 will be operating under predetermined conditions against a substantially non-compressible fluid. It will be apparent that during the 5 spring compressing operation the fluid pressure underneath the piston 63 will tend to lift the valve 65 from its seat thereby permitting flow of oil through the passages 64 so that the piston 63 may be moved to its lower position 10 without appreciable fluid resistance. This position is illustrated in Fig. 5 where- 15 in the bell crank 31 has fully compressed the spring prior to the actual switch closing operation. For the purpose of maintaining the 15 valve 65 out of engagement with the piston 63 so that the cylinder 60 may now be moved with respect to the stationary piston 63 during the switch closing operation, there is provided a stationary stop member 68 for en- 20 gaging the lower extension 66' of the valve stem so as to insure that the passages 64 are unobstructed during the switch closing operation.

The operation of the hydraulic coupler in 25 permitting trip-free action and in opening the circuit breaker is believed to be apparent. Immediately upon release of the compression spring in response to collapse of the tripping toggle, the forward movement of the piston 30 63 with respect to its cylinder immediately closes the valve 65 so that the piston is acting on a confined body of oil. Accordingly, the piston 63 and its cylinder serve as thrust-transmitting structure and move together as 35 a unit to cause rapid opening of the circuit breaker.

In the event that the tripping magnet is energized during the closing movement of the breaker, the compression spring is, of course, 40 instantly released and tends to force the piston 63 upwardly at high speed. This action immediately closes the valve 65 so that the piston is acting as in the previous instance, on a confined body of oil. It is therefore ap- 45 parent that tripping of the operating mechanism, and concurrent release of the compression spring at any point in the closing movement of the breaker causes the operating rod 6 to be actuated upwardly at high speed with- 50 out shock or impact.

Under certain operating conditions, as for example, where the electric motors derive their power from storage batteries, it may be desirable to utilize one motor instead of two 55 for effecting the individual switching operations above described. There is illustrated in Fig. 6 an arrangement wherein the use of a single motor for performing the above operations is possible. As in the previous instance, the operating rod 6 and the 60 compression spring 25 are provided with operating bell cranks 70 and 71 respectively, which are each pivotally mounted at a common center 72. The bell crank 70 is connected to an operating toggle 73-74 whose

central pivot 75 is connected through a link 76 to a centrally pivoted operating lever 77. The bell crank 71 is connected through a similar operating toggle 78-79 to the centrally pivoted operating lever 80. In the position illustrated, the central pivot 81 of the toggle 78-79 engages a stationary stop 82 for holding the toggle in an overset, locking position. The stop 82, it shall be noted, is likewise adapted to be engaged by the central pivot 75 of the toggle 73-74 for a similar purpose. The links 74 and 79 of the above described operating toggles are each connected at a point 83 to the tripping toggle 46, and to a pivoted link 84 forming there- 80 with, as in the previous instance, a compound toggle arrangement. The toggle 46-46' coacts in the manner previously described with the tripping lug 48 and magnetizable core 51 of the tripping magnet for control- 85 ling the common pivot 83 of the toggles 73- 74 and 78-79.

For the purpose of operating the levers 77 and 80 individually and in proper sequence to perform the spring compressing and switch closing operations, the single motor 85 is connected through its centrifugal flyball linkage 86 to an operating link 87. The operating link has a slot 88 within which a lug 89 fixed at one end of the lever 80 may slide. 90 Pivotally mounted as at 90 to the upper end of the lug 87 is a catch 91 normally biased by a spring 92 in a clockwise direction. The catch 91, in a manner hereinafter described 95 is adapted to hook over and engage a pin 93, secured at one end of the lever 77 for rotating the lever in a counterclockwise direction and effecting closing of the breaker.

Referring more particularly to Figures 7, 8 and 9 wherein different operating positions of the link 87 are illustrated, the link in Fig. 7 is in position prior to starting the spring compressing operation. As will be noted, both levers 77 and 80 are in the open circuit positions, and the lug 89 is near the top of the slot 88 so that downward movement of the link 87 will be effective to cause compression of the spring. For the purpose of disengaging the catch 91 from the lever 77 during this first operation, the top of the slot 88 is spaced 100 slightly from the lug 89, and the lug is likewise provided with a detent 94 adapted to engage a cam surface 95 of the catch 91. The catch 91 is limited with respect to clockwise movement by a pin 96 in the link 87. During initial downward movement of link 87 in response to energization of the motor 85, the lug 89 remains stationary with the result that the catch 91, which is carried downwardly by the link 87, is engaged by the detent 94 so 110 as to cam the catch 91 in a counter-clockwise direction out of engagement with the pin 93. This operation is clearly illustrated in Fig. 8 wherein the lever 80 has been moved 115 to the position illustrated in Fig. 6 showing 120

the spring 25 compressed and the toggle 78—79 straightened to an overset, locking position. The motor 85 is now deenergized so that the centrifugal fly-ball linkage 86 may collapse or straighten under the influence of 5 springs or other suitable resetting means (not shown) causing return of the operating link 87 to a position to operate the lever 77 and close the circuit breaker.

10 In Fig. 9 the link 87 is illustrated in a position just prior to its link-engaging operation. The link 87 is of course free to move with respect to the lever 80 and lug 89 by reason of the elongated slot 88 and as the 15 catch 91 approaches and engages the pin 93 on the link 77 it is at first cammed along its surface 91' in a counterclockwise direction, thereby permitting the catch 91 to slide over and hook on to the pin 93. Once the 20 detent has engaged the pin 93 it is resiliently held in such position by the spring 92 so that subsequent energization of the motor 85 and downward movement of the link 87 is effective to 25 rotate the lever 77, straighten the toggle 73—74, and move the rod 6 to the circuit closing position.

As in the arrangement wherein two motors are used, the common tripping toggle 46 is adapted, when it collapses, to shift the common pivot 83 of both toggles in an upward direction so as to cause both of the operating toggles simultaneously to collapse, thereby permitting the spring 25 to cause, in the manner previously described, rapid opening 35 movement of the circuit breaker.

It is apparent that the hydraulic coupler illustrated in Figs. 4 and 5 may be connected to the bell cranks 70 and 71 in the manner previously described for the purpose of obtaining trip-free action without shock or impact.

Another arrangement for compressing the opening spring and closing the circuit breaker in sequence and independently of each 45 other while permitting desirable trip-free action, is illustrated in Figs. 10-12 inclusive. In this arrangement a suitable source of power, as a single motor, may be used, connected to a rotatable shaft 100. Upon the 50 shaft are mounted the cams 101—102 for operating respectively the spring compressing lever 103 and the switch operating lever 104. The compression spring 105 is disposed between the operating rod 6 and the operating 55 end of the lever 103 which has a central fixed pivot 103'. The operating faces of the cams 101 and 102 coat with rollers mounted at the ends of the levers 103 and 104 respectively. Tripping mechanism for the breaker and 60 spring is diagrammatically illustrated by a pivoted bell crank 106 pivotally connected, as at 104', at one end to the lever 104 and having a roller at its other end for engaging the pivoted restraining lug 107, controlled by 65 a tripping magnet 108. In Fig. 10 the appa-

ratus is in the open circuit position with the spring expanded.

The initial closing operation is effected by starting the cams which move together on the shaft as a unit, in clockwise rotation. When the cams have completed half a revolution, 70 as illustrated in Fig. 11, the cam 101 has rotated the lever 103 in the clockwise direction and compressed the spring. The lever 104, however, has remained stationary during 75 this operation since the camming surface of the cam 102 has so far been concentric with respect to the shaft 100. As the cams continue to rotate until substantially a complete revolution has been made, as illustrated in 80 Fig. 12, the lever 104 is rotated in counterclockwise direction, the pivot 104' being held stationary by the locked bell crank 106, to cause closing of the breaker. During this movement the cam 101 permits a like amount 85 of counterclockwise rotation to the lever 103 so that the spring is retained in its properly compressed position between the operating rod 6 and the lever 103 during the entire closing movement of the breaker. Accordingly, the spring is effective to react upon the 90 operating rod 6 at any time during the closing movement without shock or impact so as to afford the desired trip-free action. The tripping action is believed to be apparent 95 from the above description. Upon release of the bell crank 106 in response to actuation of the tripping means, it is urged in a clockwise direction by the spring to permit opening of 100 the breaker.

For the purpose of clearness and simplicity in disclosure, the energizing and control circuits for the motors in various forms of my invention above described have been omitted, and it shall be understood therefore that the 105 individual circuit controlling operations may be entirely under the control of an operator, as by push buttons, or if desired, suitable means well known in the art may interconnect and interlock the mechanism so that the 110 motor mechanism coacting with the powerful opening spring is energized in response to opening movement of the breaker, thereby automatically recharging the opening spring.

It shall be understood that my invention 115 is not limited to the specific details of construction or arrangement thereof herein illustrated, and that changes or modifications may occur to one skilled in the art without departing from the spirit of my invention.

What I claim as new and desire to secure by Letters Patent of the United States, is:—

1. A switch operating system comprising a circuit breaker, energy storing means for effecting rapid opening movement of said circuit breaker, and electromotive means arranged to close said circuit breaker and effect an energy storing operation on said first-named means, said electromotive means being adapted to effect said energy storing 125 130 135

operation independently of said circuit closing operation.

2. A switch operating system comprising a circuit breaker, energy storing means for causing opening of said breaker at high speed, and electromotive means effecting closing movement of the circuit breaker and an energy storing operation on said means, said electromotive means adapted to effect said energy storing operation prior to and independently of the circuit closing operation.

3. A switch operating system for a large capacity circuit breaker comprising an opening spring, electromotive actuating means, mechanism operatively connecting the electromotive actuating means to said opening spring and to the circuit breaker arranged to effect compression of the opening spring and closing of the circuit breaker, and a common trip for said mechanism causing release of said spring and consequent opening movement of the circuit breaker.

4. A switch operating system comprising a circuit breaker, energy storing means for causing rapid opening movement of the breaker, an operating mechanism connected to said breaker for closing the same, an operating mechanism connected to said means for effecting an energy storing operation thereon, said last named mechanism adapted to be operated prior to said switch closing mechanism, and a common tripping means interconnecting said mechanisms whereby said energy storing means is released to cause opening of the breaker at high speed.

5. A switch operating system comprising a circuit breaker, spring means for causing opening of said breaker at high speed, and electromotive means effecting closing movement of said breaker and compression of said spring means, said electromotive means being effective to compress said spring means independently of and prior to said circuit closing movement whereby the energy stored in the spring means is effective when released to cause rapid opening movement of the breaker.

6. A switch operating system for a large capacity circuit breaker including a switch operating rod comprising an accelerating opening spring, electromotive actuating means, a crank operatively connected to said accelerating spring for effecting compression of said spring, a crank operatively connected to said switch operating rod for effecting switch closing movement thereof and engagement with said spring, said cranks operatively connected to the electromotive actuating means for transmitting power to perform said spring charging and switch closing operations, and a tripping mechanism common to said cranks effecting simultaneous release of said spring and opening movement of the switch operating rod.

7. A switch operating system for a large capacity circuit breaker comprising opening

and closing mechanism, a compression spring adapted to store energy for causing opening movement of the circuit breaker at high speed, tripping mechanism responsive to a predetermined condition in the circuit to be controlled for permitting release of energy in said spring and opening movement of the breaker mechanism, and electromotive means effecting directly compression of said spring and closing movement of the breaker in individual sequential operations of the electromotive means.

8. A switch operating system for a high capacity circuit breaker comprising opening and closing mechanism for the breaker, a spring adapted to coact therewith for causing opening movement of the breaker at high speed, toggle structure operatively connected to the operating mechanism for causing closing movement of the breaker, toggle structure operatively connected to said spring for performing an energy storing operation thereon, tripping mechanism common to said toggle structures for permitting simultaneous release of energy in the spring and opening movement of the breaker, and motive means operatively associated with said toggle structures.

9. A switch operating system for a high capacity circuit breaker comprising operating mechanism for the breaker, spring means adapted to store energy for causing opening movement of the mechanism at high speed, toggle structure operatively connected to the operating mechanism for transmitting motion to cause closing movement of the breaker, toggle structure operatively connected to said spring means for transmitting force to perform an energy storing operation thereupon, tripping mechanism common and operatively connected to said toggle structures for permitting collapse thereof in response to a predetermined circuit condition whereby the energy stored in the spring means is effective immediately to cause opening of the breaker, and electromotive means operatively associated with said toggle structures for effecting in sequence the energy storing operation and the switch closing movement.

10. A switch operating system for a high capacity circuit breaker comprising a switch operating member, a spring coacting with said member for effecting high speed opening of the breaker, electromotive means effecting an energy storing operation on said spring, the electromotive means subsequently effecting closing movement of the breaker, and a unidirectional thrust coupling interconnecting said member and spring for transmitting without shock immediate reaction of the spring to said member at any time during the closing movement of the breaker.

11. A switch operating system for a high capacity circuit breaker comprising an operating member, spring means operatively re-

lated to said member for causing opening movement of the breaker at high speed, motive means for performing in sequence an energy storing operation on said spring means and closing movement of the breaker, tripping mechanism common to said spring means and a member for simultaneously releasing the energy in the spring means and permitting opening of the breaker, and coupling means interconnecting said spring means and a member for permitting said energy storing operation independently of movement of said member, said coupling means being adapted to transmit the reaction of said spring means to said member without shock or impact at any time during the closing movement of the breaker in response to actuation of the tripping mechanism.

12. A switch operating system for a high capacity circuit breaker comprising an operating member, a compression spring associated with the operating member for storing energy to cause opening of the breaker at high speed, an electric motor for effecting closing movement of the breaker and compression of said spring, and means for operatively connecting said motor to said spring and member in sequence whereby the spring compressing operation is effected independently of and prior to the switch closing movement.

13. A switch operating system for a high speed, large capacity circuit breaker comprising operating mechanism for the breaker, a compression spring associated therewith for storing energy to cause opening movement of the breaker at high speed, a cam adapted when actuated to cause compression of said spring, a second cam coacting therewith for causing closing movement of the breaker, and motive means for actuating said cams, the camming surfaces of the cams being so related that the spring compressing operation is effected prior to closing movement of the breaker and so that the spring is adapted immediately to react without shock upon the operating mechanism at any time during the opening movement of the breaker.

50 In witness whereof, I have hereunto set my hand this 25th day of February, 1930.

PHILIP C. CLARKE.
